ATTORNEY

UNITED STATES PATENT OFFICE.

JOHN K. CHASE, OF NEW YORK, N. Y., ASSIGNOR TO THE CHASE METAL COMPANY, OF SAME PLACE.

BOX-STRAP.

SPECIFICATION forming part of Letters Patent No. 367,892, dated August 9, 1887.

Application filed December 9, 1886. Serial No. 221,156. (No model.)

To all whom it may concern:

Be it known that I, JOHN K. CHASE, a citizen of the United States, and a resident of New York, in the county of New York and State 5 of New York, have invented certain new and useful Improvements in Box-Straps, of which the following is a specification.

My invention relates to sheet-metal straps for packing boxes or cases; and it consists in 10 a certain novel construction of such straps from pieces of waste metal, as hereinafter fully described, thereby producing an article of superior utility at a very low cost.

In the accompanying drawings, Figure 1 15 represents a plan view of a box-strap embodying my invention. Fig. 2 represents an inverted plan view thereof. Fig. 3 represents a cross-section thereof, on the line $x-x$, Fig. 1, and on a larger scale than in said figures.

20 Similar letters indicate similar parts.

The letter A indicates the pieces or sections of sheet metal composing the strap. These sections A may be of equal or unequal length, according to the state of the metal employed, 25 and they are countersunk by means of a suitable punch at points adjacent to the ends thereof, where one section overlaps the other, forming interlocking sockets or protuberances B in the double thickness of metal produced

30 by said overlapping ends, as shown in Fig. 3. One or more sockets, B may be used to each joint between the sections A, as circumstances may render expedient, and the sockets may be either round or of any other shape.

35 Each of the sections A is bent or folded over upon itself along the longitudinal edges thereof, as at C, and the folded edges of one section are fitted into those of the other at or opposite to said overlapping ends of the sections, forming double-folded edges, D, at those points.

40 Into the bight of both folded edges C of the sections is inserted a strand, e, of wire, which is continuous and extends the whole length of the strap, the same being put in place in the 45 operation of producing said folded edges, for which last-named purpose a suitable machine may be employed. If desirable, the wire strands e may be fastened at the ends, although they are generally held against displacement

by the tendency of the folded edges C of the 50 sections to bind the strands.

The sockets B assist in uniting the sections A to each other, and also act as guides or receptacles for the nails that may be used for securing the strap to the desired box, thus permitting the nails to be readily driven through the overlapping ends or portions of the sections, which effectually prevent the sections from drawing apart when in use.

The folded edges C of the sections not only 60 render the strap extremely rigid, but also act as a joint or fastening by being fitted into each other at the point of overlapping of the sections, while the wire strands e tend to resist the endwise strain on the strap, as well as 65 to increase its rigidity.

In order to insure a secure fastening of the strap to the box, the folded edges C of the sections may be arranged to extend inward to a point near the center line of the strap, as 70 shown, so that said edges are brought under the heads of the nails, and to increase the effect of the double-folded edge D the inner edge may be cut out, as at o, forming a notch to receive the extremity of the outer edge at 75 that point, said extremity of the outer edge being bent over into the notch, as more clearly shown in Fig. 3.

It will be seen that by my invention I am enabled to utilize waste metal—as, for example, 80 that obtained from refuse fruit-cans—and such material being extremely cheap the cost of the strap is reduced to a minimum, while it possesses the requisite features of a box-strap in a superior degree.

85 What I claim as new, and desire to secure by Letters Patent, is—

1. A sheet-metal box-strap constructed in sections the ends of which overlap and are countersunk to form interlocking sockets, and 90 the longitudinal edges of which are folded upon themselves at the point of overlapping, substantially as and for the purpose described.

2. A sheet metal box-strap constructed in sections the ends of which overlap and are 95 countersunk, and the longitudinal edges of which are folded upon themselves throughout the length thereof, with the edges of one section

fitted into those of the other at said point of overlapping, substantially as and for the purpose described.

3. A sheet-metal box-strap constructed in 5 sections the ends of which overlap and the longitudinal edges of which are folded upon themselves, in combination with re-enforcing strands of wire arranged in the bights of said folded edges, substantially as and for the purpose described.

Signed at New York, in the county of New York and State of New York, this 7th day of December, A. D. 1886.

JOHN K. CHASE.
